RECORD CHANGER TONE ARM OR SIMILAR ARTICLE

Martin C. Reed, Roselle, Bert L. Altmann, Chicago,
William A. Wagner, Park Ridge, and James G. Aurand,
Chicago, Ill., assignors to Warwick Electronics Inc.,
Chicago, Ill., a corporation of Delaware

Filed Nov. 18, 1964, Ser. No. 82,671

Term of patent 14 years

(Cl. D26—14)

FIGURE 1 is a perspective view of a record changer tone arm or similar article, showing our new design;

FIGURE 2 is a right side elevational view to an enlarged scale;

FIGURE 3 is a top plan view, on the same scale as FIGURE 2;

FIGURE 4 is a left side elevational view, on the same scale as FIGURES 2 and 3; and

FIGURE 5 is a front elevational view thereof, on the same scale as FIGURES 2-4.

We claim:

The ornamental design for a record changer tone arm or similar article, as shown.
